Games Corporation, Chicago, Ill., a corporation
of Illinois

Application May 1, 1935, Serial No. 19,237

4 Claims. (Cl. 312—35)

This invention relates to a vending machine.

It is an object of this invention to provide an improved vending machine which is relatively simple and inexpensive in construction and efficient in use.

Another object of the present invention is to provide certain improvements upon the vending machine shown and described in our copending application, Serial No. 19,236 filed May 1, 1935 on a vending machine.

Other objects will appear hereinafter.

The invention consists in the novel combination and arrangement of parts to be hereinafter described and claimed.

15 The invention will be best understood by reference to the accompanying drawing, showing the preferred form of construction and in which:

Fig. 1 is a perspective view of a vending machine embodying a preferred form of the invention;

Fig. 2 is a fragmentary vertical sectional view of the same;

Fig. 3 is a top plan view, partly in section; and

Fig. 4 is a vertical sectional view, on line 4—4 in Fig. 3.

A preferred form of the present invention is shown in the drawing, is therein generally indicated at 10, and comprises a cabinet 11 which includes an article storage or display compartment 12 and a compartment 13 which is arranged below the display compartment 12 and houses the operating mechanism of the machine.

Arranged in the cabinet 11, between the article storage or display compartment 12, and the lower compartment 13, is a horizontal partition 14 in which is provided a centrally disposed opening 15 (Fig. 2).

Arranged in the opening 15, and supported from the partition 14, by means of brackets 41, is a relatively stationary disc or table 16 and surrounding the table 16 is a turntable 17. This turntable 17 is rotatably mounted in and guided by rollers 42 which are suitably journaled, in brackets 43 which are mounted upon the partition 14 (Figs. 3 and 4); the stationary table 16 being arranged in a central opening 18 which is provided in the turntable 17.

Attached to the turntable 17, and depending from the bottom side thereof, is a ring gear 19, which is provided with teeth 20, and meshing with the teeth 20 of the ring gear 19 is a gear or pinion 21, which is mounted on a horizontal shaft 22. Carried by the shaft 22 is a beveled gear 23 which meshes with a beveled gear 24 and the gear 24

is attached to a rotatable horizontal shaft 25 (Fig. 3). Carried by the shaft 25, exteriorly of the front wall 26 of the cabinet 11, is a handle or "selector" 27.

Surrounding the turntable 17 is an annular retaining wall 28 which is mounted upon the brackets 43 by means of the vertical extensions 44 and provided in this retaining wall 28 is a cut-out portion or opening 29 (Fig. 3); and adapted to be moved through the opening 29, over the upper surface of the turntable 17 and over the relatively stationary table 16, is an article ejecting arm 30 which is carried by a boom 31, the boom 31 being pivotally mounted in the cabinet 11, as at 32, for horizontal movement relative to and over the turntable 17 and the stationary table 16.

Provided in the stationary table 16 is an eccentrically arranged opening 33 (Fig. 4) and rotatably mounted in this opening 33 is a member 34 which has a "nose" or "sweep" portion 40 which is movable over the upper surface of the stationary table 16. Provided in this member 34 is an article receiving and dispensing opening 35 and arranged in the cabinet 11 below, and in communication with, the article-receiving opening 35 is an article delivery chute 38 which communicates with an article delivery door 39 which is pivotally mounted in the front wall 26 of the cabinet 11 (Fig. 2).

Attached to the member 34 at the bottom thereof is a ring gear 36 and meshing with this ring gear 36 is a pinion 37.

Operation

A quantity of vendible articles (not shown) are adapted to be supported upon the turntable 17 and the turntable 17 may be rotated, so as to position a preselected article thereon in registration or alignment with the opening 29 in the retaining wall 28, by rotating or manipulating the "selector" or handle 27, this movement of the selector 27 being transmitted, by way of the shaft 25, gear 24, gear 23, shaft 22, and gear 21 to the ring 19—20 which is attached to the turntable 17, and in this manner the turntable 17 may be rotated, relative to the stationary table 16, and relative to the boom 31; the turntable 17 being guided during its rotation by means of the guide rollers 42.

The boom 30 and the article-ejecting arm 31 carried thereby may be operated by any suitable means, such as the means shown and described in our above identified copending application, and when the boom 31 is operated (clockwise, Fig. 3)

the article-ejecting arm 30 carried thereby is moved through the cut-out portion or opening 29 in the retaining wall 28 over the upper surface of the turntable 17 and over the upper surface of the stationary table 16 so that the article-ejecting or dispensing arm 30 may engage a vendible article disposed upon the turntable 17 between the cut-out opening 29 in the retaining wall 28 and the article-receiving or dispensing opening 35; and thus push the preselected article off from the turntable 17, over the stationary turntable 16, into the article-receiving or dispensing opening 35, whence the thus vended article will fall into the delivery chute 38 and drop down the same to the article delivery door 39, from which it may be removed by the operator of the machine.

The "nose" portion 40 of the member 34 provides a "sweep" which may be moved over the upper surface of the stationary table 16 by rotation of the member 34, and the rotation of this member 34 may be effected by any suitable means, such as that shown and described in our above-identified copending application.

28 The function of this "sweep" 34-40 is described in our above-identified copending application, namely, to remove from an advantageous position upon the stationary table 16, in the path of movement of the article-ejecting arm 30, any vendible article or articles which may have been fraudulently moved into such an advantageous position, between the opening 29 in the retaining wall 28 and the article-receiving opening 35, by rocking or tilting the machine from its normal or proper operating position.

Only such parts of the present vending machine have been shown and described as are necessary for an understanding of the same and of the principal differences between the present machine and that shown and described in our above-identified application, it being noted that the principal differences between the present machine and that shown and described and claimed in our aforesaid copending application reside in the fact that in our aforesaid copending application the "sweep" (similar to the member 34-40) is rotatably mounted in the turntable, rather than in a relatively stationary table, as in the present machine, and hence the article delivery opening is likewise disposed within the marginal edge of the turntable and is concentric relative to the same, rather than being eccentrically arranged relative thereto as in the present machine; and in this connection it will be noted that the "hazard", or difficulty encountered by the operator of the present machine in ejecting an article from the turntable 17 into the article-dispensing opening 35 is greater in the present machine than in the machine shown in our aforesaid application, by reason of the arrangement of the parts in the present machine relative to each other.

While we have illustrated and described the preferred form of construction for carrying our invention into effect, this is capable of variation and modification, without departing from the spirit of the invention. We, therefore, do not wish to be limited to the precise details of construction set forth, but desire to avail ourselves of such variations and modifications as come within the scope of the appended claims.

Having thus described our invention what we claim as new and desire to protect by Letters Patent is:

75 1. In a vending machine, the combination of:

a cabinet including an article storage or display compartment; an article-supporting turntable rotatably mounted in said article display compartment and having a centrally disposed opening formed therein; a relatively stationary article-supporting table arranged in the said centrally disposed opening in said turntable and having an article-receiving opening therein; means for rotating said turntable relative to and around said relatively stationary table; a boom 10 movably mounted in said article-storage compartment for movement relative to and over said tables and including an article-ejecting arm movable over said turntable and over said relatively stationary table toward said 15 opening so as to eject a vendible article off from said turntable over said relatively stationary table into said article-receiving opening.

2. In a vending machine, the combination of: a cabinet including an article storage or display 20 compartment; an article-supporting turntable rotatably mounted in said article display compartment and having a centrally disposed opening formed therein; a relatively stationary article-supporting table arranged in the said centrally disposed opening in said turntable and having an opening therein; a member rotatably mounted in the said second-named opening including a portion movable relative to and over the upper surface of said relatively stationary 30 table and having an article receiving opening formed therein; means for rotating said turntable relative to and around said relatively stationary table; a boom movably mounted in said article-storage compartment for movement relative to and over said tables and including an article-ejecting arm movable over said turntable and over said relatively stationary table toward said 35 article receiving opening so as to eject a vendible article off from said turntable over said 40 relatively stationary table into said article-receiving opening.

3. In a vending machine, the combination of: a cabinet including an article storage or display compartment; an article-supporting turntable 45 rotatably mounted in said article display compartment and having a centrally disposed opening formed therein; a relatively stationary article-supporting table arranged in the said centrally disposed opening in said turntable and 50 having an article-receiving opening therein; means for rotating said turntable relative to and around said relatively stationary table including a member movably mounted in a wall of said cabinet; a boom movably mounted in said article-storage compartment for movement relative to and over said tables and including an article-ejecting arm movable over said turntable and over said relatively stationary table toward said 55 article-receiving opening so as to eject a vendible 60 article off from said turntable over said relatively stationary table into said article-receiving opening.

4. In a vending machine, the combination of: a cabinet including an article storage or display 65 compartment; an article supporting turntable rotatably mounted in said article display compartment and having a centrally disposed opening formed therein; a relatively stationary article-supporting table arranged in the said centrally disposed opening in said turntable and having an opening therein; a member rotatably mounted in the said second-named opening including a portion movable relative to and over the upper surface of said relatively stationary 70 table into said article-receiving opening.

table and having an article receiving opening therein; means for rotating said turntable relative to and around said relatively stationary table including a member movably mounted in a wall of said cabinet; a boom movably mounted in said article-storage compartment for movement relative to and over said tables and including an article-ejecting arm movable over said

turntable and over said relatively stationary table toward said article-receiving opening so as to eject a vendible article off from said turntable over said relatively stationary table into said article-receiving opening.
